UNITED STATES PATENT OFFICE.

CHRISTER PETER SANDBERG, OF LONDON, ENGLAND.

SLEEPER FOR PERMANENT WAY.

1,194,240.

Specification of Letters Patent. Patented Aug. 8, 1916.

Application filed May 17, 1915. Serial No. 28,806.

To all whom it may concern:

Be it known that I, CHRISTER PETER SANDBERG, a subject of the King of Great Britain, residing in London, England, have 5 invented certain new and useful Improvements in Sleepers for Permanent Way, of which the following is a specification.

It has frequently been proposed to stamp or cut from a metal sleeper tongues which 10 when turned up each from its own individual slot serves to hold a rail. When this is done in such a manner that the tongues are turned up toward each other plenty of metal is available for forming the two jaws 15 of a chair and there is a seating for the rail between the jaws. When, however, the tongues are turned up away from each other, the metal left as a seating so far reduces that available for holding the rail, that only 20 one chair jaw has been formed, the other tongue serving merely as a clip for the flange or lower head of the rail; or at best short abutments for specially shaped keys 25 have been formed, which cannot be regarded as constituting an efficient support for the rail.

The principal object of the present invention is to provide a combined sleeper and chair of exceedingly simple and inexpensive 30 construction which will conform to the accepted and demonstrated standards of the practical art and which can be used for the heaviest and fastest main line traffic, in such use maintaining a perfectly safe and secure 35 grip of the rail.

By my invention I turn up both the tongues from one and the same slot, and thus form from the metal of the sleeper one or more jaws of a chair which is preferably 40 of the type wherein the rail is held in position by a wedge or wedges at one or both sides, leaving no metal between separate slots to act as a seating for the rail, which is instead supported by the parts of 45 the sleeper, made suitable for the purpose, on each side of the slot.

The relative lengths of the tongues made by cutting the metal depends of course upon the position of the transverse cut made 50 in severing the metal to be turned up from the slot to form the two tongues. If the cut is made about the middle of the slot and at right angles to the edge of the sleeper, the tongues are of sufficient length to serve as

jaws of a chair for supporting a rail of certain rail sections, being long enough for this purpose, whether one jaw be bent to abut directly against the web of the rail, the other jaw holding a key, or whether both jaws are provided with keys. If the cut is 55 made at unequal distances from the ends of the slot, one tongue may constitute a jaw and the other merely a clip for the flange or lower head of the rail.

In making the jaws of a chair for some 60 rail sections, however, a simple transverse cut at right angles to the edge of the sleeper does not provide tongues of sufficient length for forming the two jaws. In this case, therefore, I cut the metal transversely along a line inclined to the edge of the sleeper or along a curved or stepped or otherwise irregular line. In this manner 65 each tongue is longer or of greater effective length at one part and shorter at the other 70 parts than it would have been had the cut been at right angles to the edge of the sleeper. For example the transverse cut 75 may be such as to leave one tongue with a single tooth at the middle part of its width 80 and the other with two teeth, one at each side. An exaggeration of this leads practically to two tongues forming one of the jaws and a single tongue forming the other.

When strengthening metal for the jaws 85 is desirable this may be in the form of a rib or ribs preferably on the upper face of the sleeper or tongue, although other ribs for strengthening the sleeper may be on the under face. Corrugations are an obvious 90 equivalent of ribs. When the strengthening metal is a thickened portion of the metal substantially co-extensive in width with the tongues, it may be on the upper or under face of the sleeper or tongue or on both. 95

The accompanying drawings illustrate several forms of the invention.

Figure 1 is an elevation of one end of a sleeper showing a chair formed of tongues of the metal according to the invention. 100 Fig. 2 is a plan of same. Fig. 3 is a side elevation and Fig. 4 a top plan view of one end of a sleeper showing a modified arrangement. Fig. 5 is a section on line 5—5 of Figs. 3 and 4. Fig. 6 is an elevation 105 showing another modification. Fig. 7 is a plan of same. Fig. 8 shows a section on line 8—8 of Figs. 6 and 7. Fig. 9 is a similar

view on line 9—9 of Figs. 6 and 7. Fig. 10 is a transverse section of a sleeper showing another modified arrangement of cutting the jaws. Figs. 11 and 12 are views similar to 5 Figs. 8 and 9 and respectively showing a further modification.

In the simplest form of the invention shown in Figs. 1 and 2, the plate or blank A forming the body of the sleeper is of uniform section throughout and at the place where the chairs or rail jaws are to be formed a longitudinal slot C is cut or stamped in the metal and the strip of metal filling the slot is transversely severed in the center, the two tongues B thus formed being turned upward and away from one another to form the jaws of the chair to receive the rail. As shown in these two figures the chair is constructed to receive a flanged rail 10 D, which is held in position between the jaws, which are preferably somewhat inclined to one another, by a distance piece E and a wedge or key F. The distance piece E is preferably grooved or formed with shoulders e to embrace the sides of the jaw B to prevent its movement longitudinally of the rail. The end portion of the sleeper may be bent slightly upward to give the necessary cant to the rail. The sleeper is 15 preferably made of such width that the parts a at the side of the slot B are of sufficient strength to bear the rail without any special reinforcement.

The construction shown in Figs. 3 to 5 is 20 similar to that above described except that the sleeper A is strengthened by a longitudinal rib a' on its upper face which is so arranged that it coincides with the tongues B and, when these are cut and bent upward, 25 serves to reinforce them. Strengthening ribs a² may also if desired be formed on the underside of the sleeper A.

In the arrangement illustrated in Figs. 6 and 9 the invention is shown as applied to 30 the formation of a chair in which the jaws are required to be longer than can be obtained by a simple transverse cut of the strip forming the jaws, as for instance, when a bull head rail is used, and one of the jaws is required to abut directly against the web of the rail. To obtain such increased length of 35 the jaws B the strip of metal forming the jaws is cut or severed along a stepped or irregular line so that the jaws B are of the shapes shown in Figs. 8 and 9. In this case a wedge or key F alone is required to secure the rail D.

It will be obvious that to obtain still 40 longer jaws, or to obtain jaws of equal length from a shorter slot, that is to say to permit of the jaws being brought closer together the depth of the stepping in such transverse cut may be increased somewhat in the manner indicated in Figs. 11 and 12. 45 Another method of cutting the tongues to

obtain greater length is shown in Fig. 10. In this case the tongues B are formed by a straight cut made at an inclination across the strip cut out from the slot C in the sleeper.

Having thus described my invention and the best means I know of carrying the same into practical effect, I claim:

1. A metal sleeper having jaws formed integral with the metal of the sleeper and turned up from a single slot to provide the jaws of a chair in which the track rail is retained by the coöperation of both of said jaws with the web of the rail and by the co-operation with one of said jaws of a wedge interposed between it and said web, said sleeper having seatings for the rail integral therewith at opposite sides of said slot.

2. A metal sleeper having track-rail-receiving jaws formed integral with the metal of the sleeper and turned upward and away from one another from a single slot to provide the jaws of a chair in which the track-rail is retained by the coöperation of both of said jaws with the web of the rail and by the co-operation with said jaws of members interposed between them and said web, said sleeper having seatings for the rail integral therewith at opposite sides of said slot.

3. A metal sleeper having a strip cut from the upper portion thereof and severed approximately at its center to form jaws of substantially equal length, said jaws being turned up from the single slot formed by cutting the strip and providing a chair in which a track rail is held by the coöperation of both of said jaws with the web of the rail and by the co-operation with one of said jaws of a wedge interposed between it and said web, said sleeper having seatings for the rail integral therewith at opposite sides of said slot.

4. A metal sleeper having a strip cut therefrom and struck upwardly and leaving a single slot, the strip being transversely severed to provide jaws of approximately equal length but longer than half the length of the slot from which they are formed, the jaws serving as a chair to receive a track rail and being each formed to coöperate with the web of the rail.

5. A metal sleeper having jaws formed integrally with the metal of the sleeper and turned up from a single slot to form a chair to receive the track rails in which the metal strip cut from the sleeper to form the jaws is severed irregularly so as to form jaws both of which coöperate with the web of the rail and the sum of whose over all lengths is greater than that of the slot from which they are cut.

6. A metal sleeper having jaws formed integrally with the metal of the sleeper and turned up from a single slot to form a chair to receive the track rail in which the sleeper

is formed with a longitudinal rib upon its upper face adapted to coincide with and reinforce said jaws.

7. A metal sleeper having jaws formed integral with the metal of the sleeper and turned up from a single slot to form a chair to receive the track rail, said jaws being both fashioned to coöperate with the web of the rail and the sleeper being formed on its 10 under side with longitudinal ribs spaced outside the slot from which said jaws are formed.

8. A metal sleeper having jaws formed integral with the metal of the sleeper and

turned up from a single slot to provide the 15 jaws of a chair in which the track-rail is retained by the coöperation of both of said jaws with the web of the rail, said sleeper having seatings for the rail integral therewith at opposite sides of said slot.

20 In testimony whereof I have signed my name to this specification in the presence of two subscribing witnesses.

CHRISTER PETER SANDBERG.
